UNITED STATES PATENT OFFICE.

CHARLES NOBLE, OF PHILADELPHIA, PENNSYLVANIA, ASSIGNOR TO HIMSELF, F. P. NICHOLSON, AND C. NOBLE, OF SAME PLACE.

DESIGN FOR DOORS OF COOKING-STOVE.

Specification forming part of Design No. **7,607**, dated August 4, 1874; application filed July 22, 1874.
[Term of Patent 7 years.]

To all whom it may concern:

Be it known that I, CHARLES NOBLE, of the city of Philadelphia, Pennsylvania, have invented a Design for Doors of Cook-Stove, of which the following is a specification:

In the accompanying drawing, Figures 1 and 2 are views of the large and small doors of a cook-stove ornamented in accordance with my design.

The most prominent feature of the design is a circular medallion, A, which occupies the center of the door, the said medallion being an imitation of the Grangers' seal, and its principal characteristics being an endless chain of links, a wheat-sheaf, and a plow. Above and below the medallion are tablets *a* and *b*, on which are marked the word "Grange" and the date. The door is edged by a plain bead-

ing, *c*, within which, at each corner, is a foliated ornament, *f*.

In the small door, Fig. 2, the tablets *a* and *b* are omitted.

I claim—

1. The design for a stove-door ornamented by the medallion A, shown and described.
2. The whole design, including the medallion A, tablets *a* and *b*, and foliated ornaments *f*.

In testimony whereof I have signed my name to this specification in the presence of two subscribing witnesses.

CHAS. NOBLE.
